UNITED STATES PATENT OFFICE.

MARK JORDAN WOODHULL, OF ANGOLA, INDIANA.

RAILWAY-ROAD SPREADER.

1,232,641.

Specification of Letters Patent. Patented July 10, 1917.

Application filed June 19, 1916. Serial No. 104,566.

To all whom it may concern:

Be it known that I, MARK JORDAN Wood-
HULL, a citizen of the United States, residing
at Angola, in the county of Steuben
5 and State of Indiana, have invented certain
new and useful Improvements in Railway-
Road Spreaders, of which the following is
a specification.

My invention relates to railroad spreaders
10 and material distributors for constructing
and maintaining railroad roadways, by sur-
facing the road beds, distributing ballasting
and removing snow, and the like.

One of the objects of my invention is to
15 generally improve machines of this character.

Another object of my invention is to im-
prove the side-wing extending and bracing
mechanism whereby to extend the wings
20 with greater celerity and to more firmly
hold them in extended or retracted position,
or in any intermediate position.

And still another object of my invention is
to provide a scoop attachment in front of
5 the side wings, or supplementary to the side
wings, whereby to more evenly distribute
the ballasting by temporarily containing an
excess of ballasting material therein, taken
from the roadway where too great a quan-
10 tity is placed, and distributing it at points
where it is lacking to equalize the thickness
of said ballasting material.

Other, further and more specific objects
5 of my invention will become readily appar-
ent to persons skilled in the art, from a con-
sideration of the following description when
taken in conjunction with the drawings,
wherein:

Figure 1 is a plan view of a machine em-
bodying my invention showing one side
wing extended and the other side wing in-
folded or retracted.

Fig. 2 is a side elevation of the machine.

Fig. 37 is a section taken on line 37—37 of Fig. 2.

In all the views the same reference characters are employed to indicate similar parts.

My road spreading and distributing machine is organized in association with a car to be moved along the tracks of a railway, by being pushed ahead of a locomotive, and 15 supported on the car for convenient operation by one or two operators stationed thereon.

The body portion of the car comprises two centrally and longitudinally positioned 20 beams 40, 41, preferably I beams, which extend from the rear end to practically the extreme front of the body portion and two parallel, preferably, channel beams 42 and 43 with their flanges inturned. The beams 25 are joined in the usual manner, as by riveting, or otherwise, to a sheet steel or iron floor 44. This portion of the structure constitutes the body of the car, having draw-bars 45 at each end and which is supported 30 upon the trucks 46 and 47 at the front and rear ends, respectively. A bolster 48 extends transversely of the body part of the car and is secured to the beams 40 to 43, inclusive, and rests upon the bolster 49 of 35 the truck. The channel beams 42 and 43 are each mitered, as at 50, and are continued at 42' and 43', respectively, to a part 51 which is transversely disposed of and fixed to the two central longitudinal beams 40 and 41. By this arrangement the car is 40 pointed at its front end for accommodation of the plow-like wings pivoted thereto and to be hereinafter more fully described.

Those portions of the structure which I 45 have just described, except the pointed front end, are generally common to an ordinary flat car and for brevity of description I will hereinafter refer to this portion of the device as a car.

50 The parts of the machine on one side of the longitudinal median plane are substantially duplicated by similar parts on the opposite side of the central plane and therefore I will describe the parts on one side 55 and refer to the others, wherever reference is necessary, by the same reference characters with the addition of the exponent prime (').

Erected just behind the front truck 46 of 60 the car, is a wing-supporting column 38 consisting of two parallel angle irons 52 and 53, which are fixed to the side of the body of the car, and which extend thereabove in vertical parallel planes. Inside of the angle 65 bars 52 and 53 are similar, but smaller an-

gle bars 54 and 55 having their inturned flanges in substantially the same planes as are the corresponding out-turned flanges of the angle bars 52 and 53. The angle bars 54 and 55 extend only part way up to the 70 bottom of the power cylinders, and while reinforcing and strengthening the angle bars 52 and 53 serve as guides for the vertically reciprocatable head 56 that is moved in response to the fluid-pressure power-cylinder or engine 57, the piston of which is connected, as at 58, to the vertically reciprocatable post 59 within the composite-column 38 formed of the angle bars 52 to 55 inclusive. Secured to the outwardly extending flanges of the angle bars 52 and 53 and inside the column 38, are channel bars 60 and 61, to form guides for the vertically movable post 59. The reciprocatable post 59 is composed of side plates 62 and 63, spaced 75 apart by sleeves 70 and 71, so as not to clamp or bind the channel beams 60 and 61 when it is being vertically moved. An outside plate 72, reinforces the plate 62, and bolts 73 and 74 pass through the spacing 80 sleeves 70 and 71 and hold the plates uniformly spaced apart. A wooden filler 75 gives stability to the post and prevents the plates, in a large measure, from warping or becoming distorted.

Secured to the lower end of the post 59 is a hinge member 76 pivoted by a vertically extending pintle 77 to a hinge member 78 carried by a casting 79 (Fig. 2 and Fig. 31). A spreader wing 80 has its inner and wider 100 end pivoted to the casting 79, by a transversely extending pintle 81. By this means the wing 80 may be swung in a longitudinal plane on the hinge 76 and in a vertical plane on the hinge pintle 81.

105 The casting 76 (Fig. 26) bears upon its rear side an extension 82 which carries a roller 83 that bears against the outside surface of the outwardly projecting flange of the angle beam 52 of the column 38. The 110 weight of the extended wing 80 is carried, to some extent, by the projection 82 and the roller 83, which reduces the friction resistance to the vertical movement of the wing 80 produced by contact between the casting 115 and the vertically extending contacting portion of the column.

A similar casting 85 (Fig. 37) is connected to the plate 62, of the vertically movable post 59, near its top, and is provided with a 120 laterally extending portion 86 bearing a roller 87 which has contact with the outwardly extending flange of the angle beam 53. The roller 87 is on the opposite side of the column, from that upon which the 125 roller 83 is situated. A strut or tie 84—composed of two members 85 and 86, telescopically engaging—are connected together, as at 87, is connected to the outer end of the wing 80, as at 88, and at its upper end to a 130

casting 89 that is hinged in the casting 85, as at 90. The hinge 90 is in the same vertical plane as the hinge 77 upon which the inner end of the wing 80 may be swung.

5 The latch or lock 91, for holding the interlocked members 85 and 86 in adjusted position will be hereinafter more fully described.

It will now be manifest that the wing 80 10 and its tie or strut 84, may be vertically adjusted by admission of fluid under pressure into the power cylinder 57, to raise or lower the wing, as may be desired. After the wing has been thus adjusted to its proper altitude, it may be maintained in adjusted position by the fluid in the cylinder or by means of a pin which may be inserted in the perforations 92 made in the bracket 56, which connects the piston of the power cylinder 57 with the vertically movable post 59, and into and through similar perforations 93 that are made at intervals through the inner projecting flanges of the angle beams 54 and 55.

25 In Fig. 12 the wings 80 are shown infolded and drawn upwardly to the highest position attainable. In such positions they will be maintained during the time when the apparatus or machine is being moved 30 from one point to another over the track prior or subsequent to being placed in operation, to avoid obstructions on the right of way.

The lower edge of the wing 80 is stiffened 35 by the angle bars 94, 95, and 96, which extend longitudinally thereof and bearing upon the front face of the angle bar 96 is a blade 97 which has a downturned point 98 which engages the material encountered by 40 the wing 80 and serves to hold it down to its work.

A power cylinder 100, one for each wing, is supported under the body part of the car and is used in conjunction with the connecting 45 mechanism to swing the wing on its hinge 76 into substantially the oblique position shown in Fig. 1.

Under the floor 44, of the car body, is another floor 102, immediately above the 50 cylinders 100 to which is secured a guide, comprising a short section of I beam 103, carrying a reciprocatable guide member 104. The piston rod 105 is connected to this member, as at 106, and is adapted to reciprocate 55 it along the guide 103 when the fluid under pressure is admitted into the cylinder 100, on either side of the piston. A lever 107, is pivoted to a bracket 108, that is secured to the side of the body part of the car, and is 60 connected to the guide member 104 by means of a link 109. It carries on its lower end, 110, another link 111, which is loosely connected to the lower edge of the wing 80, as at 112, and to the lower end of the lever 107, 65 as at 113. When the wing 80 is drawn in,

as shown in Fig. 12, the wing-operating mechanisms are in the positions shown therein, but when the wing 80 is extended, as shown in Fig. 14, the piston has been moved outwardly of the cylinder 100 and the link 70 107 occupies substantially a vertical position. When the wing 80 is extended the link 111 will permit some vertical displacement of the wing 80. The power means, consisting 75 of the piston of the cylinder 100 and connecting mechanism, is attached to the lower edge of the wing 80 because the greatest strain comes against the lower edge which is thereby resisted without distorting or bending the wing.

80 The vertically disposed wing-supporting columns 38 composed of the angle bars 52 and 53, are tied at their tops by cross beams 112 and braced by tie bars that extend from a point near the top of the column, at angles of substantially 45 degrees therefrom, and attached at their lower ends to the body part of the car. The lower ends of the columns 38 are connected together by cross beams 114.

85 The rear end of each of the wings 80, may be held in folded or retracted position, as when the spreader is being taken from place to place, without being used, during transit, by means of chains 215 that may be secured to a cross sill of the body structure of the 90 car, and by a chain comprising a turn buckle 216, a hook 217, and an eye 218 that may be fixed at a suitable point to the wing 80. The turn buckle may be used to shorten the 95 effective length of the chain so as to draw the 100 wing tightly into position and prevent its lateral vibration during transit.

100 Located at suitable longitudinal intervals along the inside of each of the wings 80, and pivotally connected thereto and to the 105 car body, are suitable two-part struts or compression beams 115, 115^a, 115^b and 115^c varying in lengths and each being capable of longitudinal extension or contraction. These struts are substantially alike, differing 110 only in their effective lengths, made necessary by the gradually increasing distance between the wing 80 and the body part of the car, when the wing is angularly displaced with respect thereto. Each of the 115 struts comprises members 116 and 116'. They are similar in cross section to the tie beam 84, which supports the outer end of the wing 80 against vertical displacement, and are shown in cross section in Fig. 24. The telescopic relation of the two co-operating 120 members is shown more clearly in detail in Fig. 23. The member 116, which is adapted to be connected to the body part of the car, in a manner to be hereinafter 125 more fully explained, is substantially an I beam and is contained between the two spaced apart channel beams 116', 116'', which are so spaced apart to permit free sliding or telescopic relation of the two 130

members. The members 85 and 86 of the tie beam 84 are constructed in substantially the same manner and operate in the same way for lengthening or shortening the effective length of the composite tie beam.

Each of the members 116 and 116' and of the tie beam 84 are uniformly perforated at intervals, as at 118, with registering perforations and preferably the perforations should be arranged in a plurality of longitudinally extending rows in each of said members, so as to be able to change the effective length of the members in relatively small gradations by means of the beam locking mechanism 91, which I will now describe.

A bracket base 119 bears upon its outer surface a bracket 120 consisting of two spaced apart members between which are pivoted curved levers 121, 122, of such length that their free ends are in substantially the same transverse plane when the levers are swung inwardly on their pivots. This bracket structure is preferably mounted upon the I-beam of the composite beam. The curved levers 121, 122 each carry on its free end a plate 124, which is pivoted to the free end of the respective levers, as at 125, to permit some slight pivotal motion so that the plates may adjust themselves to the side surface of the beam, when in operative position. Facing inwardly, and projecting from the plate 124, are a series of studs 126 which are adapted to pass through the registering perforations 118 of the beam members when such perforations are brought into register, so as to prevent any respective longitudinal movement of the beam members. Projecting vertically from the base 119 of the lock 91, is another bracket 128, which extends somewhat above the brackets 120, the outer end of which is in substantially vertical alignment with the curved lever members 121, 122, as shown in Fig. 23. A hand operable lever 129, is bifurcated to produce two spaced apart arms 130, 131, the respective arms being pivoted, as at 132, to the corresponding arms of the bracket 128. Each of the arms 130 and 131 is eccentrically curved, as at 139, and are each passed through perforations 140 near the pivotal ends of the levers 121, 122. When the beams to be locked together by the lock device have been placed in approximately the proper desired position, they may be moved to secure registration of the perforations 118 by driving a drift through any two holes 118 made in the respective beams, which will cause all of the holes to register, then the latch or beam lock 91 may be operated. When the perforations 118 of the respective beams are brought into register, the lever 129 is depressed thereby moving the pivotal arms

in Fig. 24, to full line positions bringing the plates 124 into contact with the sides of the outer beam members and causing the studs 126 to pass through the perforations of the respective beam members. This is accomplished by depressing the lever 129, which, owing to the eccentric curve 139 forces the levers 120, 121 into the full line position shown in Fig. 24 in a perfectly obvious manner, and inasmuch as contact with the lever arms 130, 131 and the arms 121, 122 is in substantially a vertical plane with the pivotal point 132 of the bifurcated levers, the levers 121, 122 will remain in the positions in which they have been placed by depression of the hand lever 129. When the lever 129 has been raised up from the depressed position, as shown in Fig. 23, the plates 124, with their studs 126, are withdrawn from contact with the beam members and out of the holes 118, and are placed in the positions shown in dotted lines in Fig. 24, whereupon the slidable beam members may be longitudinally moved, with respect to each other, to change the effective lengths of the compound beam. After the effective lengths of the compound beams have been thus adjusted it is not essentially necessary that the adjustment should be changed with each operation of the wing by longitudinally extending and contracting them. By thus shortening the effective length of the tie beam 84, the outer end of the wing 80 may be raised and by increasing the effective length of the tie beam 84, the outer end of the wing 80 may be depressed, or located in a lower horizontal plane, the wing will turn on the hinge 81 to accommodate such an adjustment.

The studs 126, on the plates 124, pass entirely through the beam members from both sides of the composite beam, so that about eight of the perforations 118 of the beams are securely pinned together by the studs 126. The arrangement is such that the studs 126 on the plate on one side of the composite beam will not interfere with the studs contained on the plate on the opposite side, as shown in Fig. 23. Of course any number of studs 126 may be employed, it is only necessary to provide sufficient area against the possible shearing effect due to the compression exerted by the outstanding wing against the respective struts tending to push them together to shorten their length or to pull them apart.

The strut member 116 terminates at its outer end, in a casting 141, which is pivoted to a bracket 142 that is fixed to the inside of the wing, as at 143, so that the inner end of the composite strut may be moved upon the pivot 143. The other, or inner end of the composite member or the beam 116 is connected to a hinge bracket 144, which is pivoted to a casting 145, as at 130

146. The casting 145 carries on its extended end, a roller 148. For each one of the struts 115—115^a—115^b and 115^c is provided a vertically extending laterally movable post, 150. Each of the posts 150 is composed of a plate 151 and two Z-bars 152 and 153, constituting a strut guide for the inner end of each of the composite struts 115, constituting a rectangular hollow post, having an outwardly facing slot 154. Between the confronting ends of the Z-bars 152, 153, is a slot which extends the full length of the post. Each of the posts is pivoted to the car body floor 44, as 15 at 155, to permit the post to swing outwardly at its lower end and inwardly at its upper end as in the dotted line position shown in Fig. 3, on said pivot. Overlying the upper end of the post 150 is a tapered 20 guide 150' to facilitate the entrance of the roller 148 into the hollow post. At the back of the post 150 is a vertically extending channel plate 156, which is secured to the side beams 42 and 43 of the car body, 25 and to transversely extending braces 157, which join the said plates, and to the angularly disposed braces 158, which extend from the lower ends of the plate 156, to the under-side of the beams 40 and 41 of the 30 car body, to strengthen the structure and hold the plates 156 strongly in their normal vertical positions. Located near the top of the post 150 are inwardly curved beam guides 159, which are secured to the sides 35 of the post and are extended forwardly in the front of the slot 154.

The composite struts 116—116', the members of which are telescopically arranged, as shown in Fig. 3, are held in vertical position by the guides 159 on the upper end of the post 150, until they descend and the roller 148 enters the interior of the post.

Similar post guards 160 are secured to the body part of the car, the confronting ends 45 of which are sufficiently far apart to permit the parallel outwardly projecting parts of the Z-bars 152 and 153 to project through the intervening space, but the back plate 156 of the post, and the contacting flanges of the 50 Z-bars will not pass through the space 161 between the post guides. One of the guides 160 is provided with a notch 162 in the upper surface of its inturned end for a latch 163 to hold the post 150 in angular position in which it may have been placed, with 55 reference to the car body, as shown in Fig. 18.

The post-holding latch consists of a latch bar 164 supported in bearings 165 secured 60 to the Z-bar 153 of the post, the bar is slotted as at 166. A spring 167 normally holds the lower end of the latch rod 164 in yielding contact in the notch 162, to support the post 150 in the angular position shown in 65 Fig. 18, when the lower end of the post has

been moved outwardly into said position. The post latch rod 164 on its upper end, carries a trigger 168, which projects into the interior of the post and is in the path of the roller 148 carried upon the upper end of 70 each of the telescopic struts that support the wings in extended position. The arrangement is such that when the pulley 148, connected on the upper end of the strut member 116, passes the trigger 168 it lifts the trigger bar 164 so that the lower end is removed from the notch 162 in the post guards 160, thereby unlocking the post and permitting it to again assume its vertical position.

The same effect can be produced at any time with regard to all of the posts, by a hand-operated lever 170, that is connected to a rotatable shaft 171, that is supported along the body part of the car, and which carries an arm 172 for each of the trigger mechanisms associated with the respective posts. The arm 172 is preferably tubular and carries on its inside a relatively slideable rod 173, bent at its end 174, which bent end enters the slot 166 of the trigger rod 164. When the manually operable arm 170 is pushed downwardly, each of the arms 173 is raised, thereby lifting the trigger rods 164 against the resilient effect of the respective springs 167, which holds the lower end of the rod in contact with the notch 162, relieving the supporting effect of the trigger and permitting the post to be returned to its vertical position by application of force to 100 push it into that position. On account of the inclined enlargement on the rod 164, as shown at 175, as the roller 148 moves upwardly against the trigger 168 carrying the latch rod 164 with it the inclined portion 105 175 permits the trigger 168 to move laterally from the path of the roller 148. When the roller 148 moves downwardly, in the channel between the Z-bars 152 and 153, when it encounters the trigger arm 168, the spring 110 176 yields to permit the trigger arm 168 to move downwardly out of the path of the roller 148, without materially affecting the trigger which holds the post in angular position, as heretofore explained.

When it is desirable to move either of the wings 80 outwardly into extended position, as shown in Figs. 1 and 3, the chain locking mechanism 215 is disconnected from the wing 80, after which air under pressure is admitted into the cylinder 100 or 100', as the case may be,—the cylinder being properly piped from a suitable reservoir of compressed air which may be furnished by the locomotive, for the purpose,—whereupon 125 the piston of the cylinder is moved outwardly, as shown in Fig. 14, until the lever 107, through the connecting link 111, moves the wing 80 outwardly. The composite struts or beams, 116—116' being connected 130

with the wing and now being substantially parallel with the guide posts 150 will move downwardly until the roller 148 enters the guide post, the arms 159 preventing outward movement of the struts 115, and guiding the roller into the post. The roller will move downwardly within the pivoted post 150, when it passes the pivoted point, whereupon the further movement of the wing 80 will move the post 150 outwardly into dotted line position, as shown in Fig. 3, permitting the roller 148 to slide down the inside of the post to its lower end. At this time the lower end of the trigger rod 164 will automatically snap into or enter the slot 162 in the guide 160 and hold the post outwardly in this angular position. It is necessary to so hold the post when the wing is being moved inwardly, so that the roller 148 will ascend the post. The hand lever 170 is now depressed, whereby the trigger will be lifted from position to hold the post outwardly, so that when the car starts ahead the stress applied to the wings will cause the struts 116-116' to move from dotted line position shown in Fig. 3 into full line position, whereupon the upper end of the casting 145 will be pushed underneath the angular projection 177, which will hold the inner end 30 of the strut in the lower end of the post 150 and prevent its upper movement therein. The retraction of the wing 80 may also be effected by the power cylinder 100 to cause the casting 145 to be moved backwardly 35 under the lug or projection 177. On the lower end of the post 150 is a cap 178 which is secured to the side members of the Z-bars 152 and 153, as at 179 (Fig. 4) and inside of this cap, and between the side members 40 of the Z-bars, is a buffer spring comprising a plate 180, held in elevated position by the spring 181, and prevented from moving out of the interior of the Z-bar members 152 and 153 by the vertically movable bolt 45 182. When the roller 148 reaches the bottom of the post it strikes this buffer and prevents dangerous shock being imparted to the machine by the impact of the descending strut.

50 The wings 80 when spread may subsequently be folded inwardly without the necessity of telescoping the strut members 116, 116' as shown in Fig. 3. Said members may be caused to extend above the post 55 150 without the necessity of shortening them by the telescopic arrangement, where the machine is to be moved only a short distance and in the path of which there is no overhead obstruction.

60 To fold the wings inwardly power is again applied to the cylinder 100 whereupon the lever 107 is moved outwardly until the parts assume dotted line positions shown in Fig. 3, whereupon the latch 168 will prevent the 65 post 150 from again assuming vertical po-

sition. Power now being again applied to the cylinder 100 will gradually draw the lever 107 into position shown in Fig. 12. This causes the rollers 148 of each of the struts to ascend the interior of the inclined 70 posts 150, when the rollers leave the posts, the flanges of the channel bars composing the member 116' of the strut, enter between the guides 159 at the top end of the post whereby the struts will be prevented from 75 falling outwardly.

A front truck vertically movable guard 183 comprising two plates, one on each side of the car, which extend from the rear point, as shown in Fig. 8, to a meeting point 80 in the same vertical plane with the draw bar 45. The rear end of the guard 183 is guided for vertical movement in a casting 184 which is secured to the body part 44 of the car. An extension 185, is angularly disposed and supports the rear end of the plate 183 and is vertically movable in the guide 184. It carries hinge members 186, for a relatively short wing 187 that bridges the space between the body part of the car and the main wing 80. The front end of the guide plates 183, where they meet in the vertical plane with the draw bar 45, carry 90 hinge members 188 and 188'. Connected to the lower end of the hinge member 188' is a 95 longitudinally extensible guide bar 190 which is pivotally connected, as at 191, to a vertically extending brace 192, which is secured to the part 46' of the car body, as at 193, and is held in place by another brace 100 194, the upper end of which is connected to the longitudinal beam 40, as at 195. The guides 184 and 185, at the rear ends of the truck guard 183, and the telescopic guide rods 190, permit vertical movement of the 105 truck guard 183 with respect to the track over which the car is passing.

Means for raising and lowering the truck guard 183 consists of the power cylinder 196, which carries on its upper end a guide 110 frame 197, within which a casting 198 is freely reciprocatable. The casting 198 is connected to the piston rod 200 and is pivotally and slidably connected to a walking beam 201, as at 202. The walking beam 201 115 is pivoted to a bracket 203 which is secured to the floor 44 of the car and which is pivotally connected to a bracket 205 carried by the walking beam, as at 206. The casting 208, carried on the upper end of the walking 120 beam 201, has some longitudinal slidable movement with respect thereto, to compensate for the angular displacement of the beam in its operative movements. The other end of the beam is provided with a casting 125 209, carrying on its outer end a link 210, which is pivoted thereto, as at 211, and which is pivoted to the hinge member at 212, whereby the front end of the guard 183 may be raised when the end 209 of the beam is 130

raised by means of the piston 196' in the power cylinder 196. Erected on the floor 44 of the car, are two outwardly extending standards 220, carrying on their outwardly projecting ends grooved sheaves or cable pulleys 221. At the upper end of the plates 183, composing the truck guard are eye brackets 222 within which to attach cables 223. In the same transverse plane with the 10 pulleys carried on the brackets 220, and located near the beam 201, are brackets 224, carrying cable sheaves, similar to the sheaves 221 carried by the brackets 220. The cables 223 are secured to the eyes 222 15 on the plates 183, pass over the sheaves 221 and 225 and are connected, as at 226, to the walking beam.

When air under pressure is admitted into the cylinder 196, above the piston 196' the 20 proximate end of the beam 201 is pulled downwardly thereby, which pulls on the ropes or cables 223, over the sheaves 221 and 225 thereby raising the rear end of the truck guard 183. The outer end 209 of the beam 25 201, is correspondingly raised, at the same time raising the front end of the truck guard 183 by connection of the pivoted link 210 therewith.

A spring latch 228 may be employed to 30 hold the beam 201 in its elevated position which will permit the truck guard 183 to descend, by the effect of gravity to its lowest position. When desirable to release the beam 201 from the latch 228 the rope 35 or cord 229, which is connected thereto, may be pulled upon, which will spring the latch member out of engagement with the casting 198 carried by the beam 201. The latch 228 may be swung out of the way by use of the 40 handle 230, when it is not desired that it shall be used for the purpose intended.

Connected to the hinges 188 and 188' are material moving plates 231 which normally lie against the angular portion of the front 45 end of the truck guard 183. Connected to each of the pivotal plates 231, as at 232, is a strut or stress rod 233, which passes through the beam 43', (Fig. 10) and behind the beam 43' is a pin 234 carried by a pivoted lever 235, supported on a bracket 236, which normally enters the rod 233 and is 50 yieldingly held therin by the spring 237 which prevents the removal of the pin except when the hand lever 235 is depressed 55 for the purpose. The rod 233 carries another perforation 238, on its outer end, (Fig. 15) in which the pin 234 is adapted to enter to hold the wing 231 in the position shown in dotted lines, in which position they 60 may be placed and by the use of which ballasting or other loose conglomerate matter may be moved from one side of the median line of the track to the other. The obliquely positioned plates, as shown in dotted 65 lines in Fig. 15, may be moved back into po-

sition shown in full lines in the same figure, in which latter position the matter to be spread on the track may be moved in opposite direction from the median line of the track. Each of the plates or wings 231 carries on its lower edge a blade 240 for direct engagement with the matter to be moved or spread over the roadway. These blades are of such length as to come within or between the rails 241 of the track.

Supplementary separable wings 242 are adapted to be secured to the wings 231, at their top and adjoining edges, and are provided with hinges 243, and are used only when snow is to be moved from the track 75 and when the snow is deeper, as in cuts along the roadway, than can be removed alone by the wings 231. The upper edges of the wings 231 are each provided with an angle iron edge 244, as are also the lower 80 edges of the wings 242, as with angle bars 245. These bars are adapted to be connected together by suitable bolts to hold the superposed wings 242 in place. The wings 242 are adapted to be swung or moved, with 85 the respective wings 231, into dotted line position, on either side of the median longitudinal plane of the machine, as shown in Fig. 15.

Secured to each of the lower edges of the 95 wings 231 is a plate 246 which is connected to the respective wings by spring connections 247 which permit the plates 246 to move rearwardly against any unyielding obstruction that may be encountered by the 100 plow or plates 231, in the progress of the machine over the track. The wings 242 are braced by vertically extending brackets 248 which are fixed to the floor 44 of the car which are connected to the respective wings 105 by links 249, as at 250.

When the device is used for spreading ballast the supplementary wings or plates 242 are not required and when the device is used for transferring ballast, or the like, from 110 one side of the track to the other, either of the wings 231 may be moved on its hinges and placed in an oblique plane, as shown in Fig. 15, without the necessity of requiring a separable additional plate for this purpose. To further strengthen the plates 242, another bracket 250, somewhat longer than the bracket 248 may be connected to the margin of the plate, as at 251 and to the body of the car, as at 252.

A truck guard 183, where it extends in front of the car, is supported at the apex of the angularly disposed parts by a brace beam 253, and also by angularly disposed brace beams 254 and 255. These beams are 125 pivoted to the guard 183, as at 256, and to a casting 257, as at 258. The casting 257 has some vertical sliding movement on the guide part 259 that is secured to the under side of the car body. This vertical relative move- 130

ment of the castings 257 and 259 and the hinging of the braces 253, 254 and 255 compensate for the vertical displacement of the truck guard 183, when the beam 201 is moved and the plow plates 231, connected thereto, are raised and lowered, by this means.

In the use of the spreader, it frequently encounters ballasting that has been dumped on the track in piles, when it becomes necessary to take some of the material that is thus deposited, and remove it to areas or places where such material is not so abundantly supplied. For this purpose I provide a scoop 260, which carries a hinge 261 for co-operation with the hinge 186, first removing the wing 80 from its place. The scoop preferably contains a major portion 262, an intermediate portion 263 and a minor portion 264, the latter bearing the hinge 261 on its inner edge. The scoop is, therefore, vertically movable with the front truck guard 183. Each one of the scoop sections is provided with a lining 265, which is hinged near the bottom, as at 266, to the scoop proper. When it is desirable to dump the scoop of the material 267, (Fig. 31) the lining 265 is pulled forwardly into dotted line position, by the hand lever 268, which is pivoted at 269, and which may be moved forwardly and held in place by the latch lever 270, engaging notches 271 in the arcuate bar 272. The lever 268 is connected to the upper edge of the lining 265, as at 273, by rod 275. For the purpose of clear illustration the lining is not shown in Figs. 27, 28 and 29. A pivoted brace 280 connects the lower part of the scoop 260 with the respective side wings 80. When the wing 80 is extended, as shown in Fig. 28, the brace 280 is relatively short, but being telescopically arranged it may be extended, as shown in dotted lines (Fig. 28) to connect with the side wing 80 when the latter is folded in, as shown in dotted lines in this figure.

The difference in the transverse dimensions of the sections of the scoop 260, as illustrated in Fig. 27, wherein the compartment 262 is of larger diameter than either of the compartments 263 and 264 provides for suitably shaping the fill or ballast adjacent the railway track, as clearly shown in this figure.

The separable bolsters 48 and 49 may be provided with castings, substantially as shown in Fig. 35. The casting 282 carries a central hub 283 which enters the opening in the casing 284. A king pin may be secured to the lower bolster 49 and passed through the hub 283. Each of the castings is provided with a trackway for the rollers 285. By this means friction is reduced and the truck is easily swiveled on its central vertical king pin bearing.

65 Located under the bolster 48, at a distance

remote from the central bearing 286, and on each side of the central bearing 286 are means for stabilizing the body part of the car to prevent it from tilting laterally upon its central bearing when greater pressure is applied to one side, as by an extended wing 80, or the like, than is applied to the other side, and consists of a housing 290 containing two pivoted pendant rocking members 291, pivoted as at 292, and adapted to bear upon a plate 295 carried by the other bolster 49. As the truck swivels, the pendants 291 turn upon their bearings and permit relative swiveling motion between the bolsters 48 and 49, all that is required for the most abrupt curve in the usual railway track, and yet they support the bolsters and the body part of the car against any vertical displacement on either side by application of pressure upon the other side of the body part of the car. The plate 293 may be of hardened material which is connected to a casting 294 of a lower grade of material which is fixed to the bolster 49, as at 295.

Spring bumpers 300 may be fitted to the sides of the car to receive the shocks or impacts of the wings 80 when they are drawn suddenly inwardly, or infolded.

The tank 301 is a reservoir for compressed air, by which the various power cylinders are operated, controllable by the connecting pipes 302 and suitable valves 303 for admitting air into the various power cylinders designed to be operated thereby. The air may be furnished from the locomotive used to push the machine or spreader, over the track, connected in any suitable manner to the air tank 301. 305 is a tool box in which to contain the tools that may be necessary for use in and around the machine.

105 A crane 305' may be erected upon the front end of the car to lift the plates 242 into positions or for handling other articles or lifting them upon the car body. It is mounted on the vertical post 306, upon which it has swiveling movement and is operable by the crank lever 307.

110 While I have herein shown a single embodiment of my invention for the purpose of clear disclosure, it is manifest that many changes may be made in the general formation, arrangement and disposition of the parts within the scope of the appended claims.

Having described my invention, what I claim is:—

1. In a machine of the character described the combination with a car; a spreader wing hinged thereto; a strut joining the wing and car; other means for extending the wing obliquely from the car and a normally vertical, hinged post, inclined by the outward movement of the wing, to guide the inner end of the strut into a substantially vertical plane when the wing is retracted. 130

2. In a machine of the character described the combination with a car; a spreader wing hinged thereto; a plurality of wing-sustaining struts joining the wing and car; means connecting the inner ends of the struts to the car, to permit the struts to assume substantially vertical positions without raising the wing when the wing is retracted; means to hold the struts in such vertical positions and means located near the hinged end of the wing to extend and retract said wing into and from an oblique plane with respect to the car.
3. In a machine of the character described the combination with a car; a spreader wing hinged thereto; a plurality of wing-sustaining struts joining the wing and car; a vertically extending guide post for each strut, hinged to the car, the lower end of which is adapted to swing outwardly; a guide carried on the inner end of each strut for sliding engagement with the respective posts; means located near the hinged end of the wing to extend and retract the wing into and from a plane obliquely of the car, whereby said struts are moved into substantially vertical planes with said guide posts when the wing is retracted and into horizontal planes when the wing is extended and means for holding the posts and wing in said positions.
4. In a machine of the character described the combination with a car; a spreader wing hinged thereto; a plurality of wing-sustaining struts joining the wing and car; a vertically extending guide post for each strut, hinged to the car, the lower end of which is adapted to be swung outwardly; a guide carried on the inner end of each strut for sliding engagement with the respective posts; an automatic lock for each post to hold it in inclined position; means located near the hinged end of the wing to extend and retract said wing into and from a plane obliquely of the car whereby said struts are moved along the inclined posts into vertical positions when the wing is retracted and means for unlocking the post to permit them to assume vertical positions.
5. In a machine of the character described the combination with a car; of a spreader wing hinged near the front end thereof; a plurality of composite wing-sustaining struts, each strut comprising two beam members slidably engaging each other, whereby to extend or contract the length of the strut, one beam of a given strut pivotally connected to the wing, the other beam having vertically sliding connection with the car; means to lock the beam members together when longitudinally adjusted to length and means to laterally move the wing on its hinge into oblique plane with respect to the car.
6. In a machine of the character described the combination with a car; of a spreader wing hinged near the front end thereof; a plurality of wing-sustaining struts, each strut comprising two beam members provided with a series of longitudinally extending perforations at their meeting ends adapted to register, and slidably engaging each other, one member of a given strut pivotally connected to the wing, the other member having vertically sliding connection with the car; locking means provided with studs to pass through registering perforations of said beam members to lock them together when longitudinally adjusted for length and means to laterally move the wing on its hinge into oblique planes with respect to the car.
7. In a machine of the character described the combination with a car; a spreader wing hinged near the front end thereof; a motor located back of the hinge, connected to the wing and adapted to directly extend and retract the wing; a series of struts pivotally connected at longitudinal intervals to the wing, and a guide for the inner end of each strut connected to the side of the car and adapted to direct the inner end of the respective struts into vertical planes when the wing is retracted and into horizontal planes when the wing is extended by the wing-moving motor.
8. In a machine of the character described the combination with a car; a spreader wing hinged near the front end thereof to permit vertical and lateral pivotal movement; a vertically movable post carrying the hinge members to which the front end of the wing is attached for elevating and lowering the wing; a motor located back of the hinge; connected to the wing and adapted to directly extend and retract the wing by direct application of force at said connection; a series of struts pivotally connected at longitudinal intervals to the wing, each strut comprising two members laterally movable with respect to each other; a guide for the inner end of one member of each strut, connected to the side of the car having slidable engagement with said strut member, and adapted to direct the inner end thereof above the car body into a vertical plane when the wing is retracted and into a horizontal plane when the wing is extended by the wing moving motor, and locking means for the slidably-engaging strut members whereby to unlock said members to permit longitudinal movement of the other member to reduce the length of the strut when in vertical position as when the wing is retracted and to lock the members in adjusted position.
9. In a machine of the character described the combination with a car; of a spreader wing having its forward end hinged to the car; a motor under the body of the car, having a reciprocating part engaging the wing to push it into obliquely-extending planes

- and to draw it in toward the car into a substantially parallel plane therewith; a plurality of telescopically-contractable struts connected at intervals to the wing, and pivoted guide members on the car, connected to the inner ends of said struts, movable to inclined positions to direct the struts into substantially vertical planes at the side of the car when the wing is moved into a substantially parallel plane with the car.
10. In a machine of the character described the combination with a car; of a spreader wing, having its forward end hinged to the car; a motor under the body of the car having a reciprocating part connected to the wing, near the front end thereof to push it into obliquely extending planes and to draw it in toward the car into a substantially parallel plane therewith; a plurality of telescopically-contractable struts connected at intervals to the wing, and pivoted guide members on the car, movable to inclined positions by movement of the wing when it is being extended, and to direct the struts into substantially vertical planes at the side of the car when the wing is being retracted and means to lock the wing and struts in retracted and vertical positions, respectively.
30. 11. In a machine of the character described the combination with a car; of a spreader wing, having its forward end hinged to the car; a motor, in the rear of the hinge having a reciprocating part to push the wing into oblique planes and to return it to retracted position, and a series of struts connected at intervals to the wing, normally in vertical planes, having slidable engagement with the car and movable from vertical planes to horizontal planes by the wing in its outward movement.
12. In a machine of the character described the combination with a car; of a spreader wing having its forward end hinged to the car; a motor, in rear of the hinge having a reciprocating part to push the wing into oblique planes and to return it to a retracted position; a series of struts connected at intervals to the wing, normally in vertical planes, having slidable engagement with the car and movable from vertical planes to horizontal planes by the wing in its outward movement and means to automatically lock the car-connected ends of said struts to the car about the time when they occupy horizontal planes.
40. 13. In a machine of the character described the combination with a car; of a spreader wing having its forward end hinged to the car; a motor on the car, in the rear of the hinge, having a reciprocating part to push the wing into an oblique plane and to return it to a retracted position; a series of rigid struts connected at intervals to the wing, normally in vertical planes, having slidable engagement with the car and movable from vertical planes to horizontal planes by the wing in its outward movement; means to automatically lock connected ends of said struts to the car about the time when they occupy horizontal planes.
50. 14. In a machine of the character described the combination with a car; of a side wing pivoted thereto; means for obliquely extending and retracting the wing; a substantially rigid strut connected to the wing; a hollow post pivotally connected to the side of the car, adapted to be inclined by outward movement of the strut; a lock to hold the post in inclined position having a part projecting into the path of the strut; means operable by the strut including said part to unlock the post when the strut is being raised to vertical position to permit the post to follow the strut.
60. 15. In a machine of the character described the combination with a car; of a spreader wing hinged near the front end thereof; a motor for moving the wing obliquely of the car and returning it to substantially parallel horizontal position therewith; a plurality of rigid struts pivotally connected at intervals to the wing and movable thereby from vertical to substantially horizontal positions when the wing is extended, and from horizontal to substantially vertical positions when the wing is retracted without changing the altitude of the wing.
70. 16. In a machine of the character described the combination with a car; of a spreader wing; a vertically movable post near the front end of the car to which said wing is hinged, a motor for moving said vertically movable post, to raise and lower the front end of the wing; another motor to extend and contract the wing and a series of rigid struts connected at intervals to the wing and to the car occupying vertical positions at the side of the car when the wing is retracted and movable into horizontal positions when the wing is extended.
80. 17. In a machine of the character described the combination with a car; of a spreader wing having its forward end hinged to the car; a truck guard surrounding the front truck of the car, and a scoop device secured to the truck guard in front of the side wing and braced to the side wing to move excess ballasting from one location to another in front of the side wing and means to change the angular presentation of the scoop to the material to be moved.
90. 18. In a machine of the character described the combination with a car; of a side wing pivoted thereto; means for

- obliquely extending and retracting the wing; a plurality of rigid struts connected at intervals to the wing; a series of hollow posts pivotally connected to the side of the car, one for each strut adapted to be inclined by outward movement of the strut; a lock for each post to hold it in inclined position, having a part projecting into the post; a roller carried by the inner end of each strut for longitudinal movement within the respective post to unlock the post when the strut is being raised to vertical position, to permit the post to follow the strut into its vertical position.
- 15 19. In a machine of the character described the combination with a car of a side wing pivoted thereto; means for obliquely extending and retracting the wing; a plurality of rigid struts pivotally connected at intervals to the wing; a series of hollow

posts pivotally connected to the side of the car, one for each strut, a lock for each post to hold it in inclined position in which position the post is placed when the wing is extended, said locking means having a part 25 projecting into the post; a roller carried by the inner end of each strut for longitudinal movement within one of the posts adapted to encounter the lock part to unlock the post when the strut is being raised to vertical position and a hand-operable means for unlocking all of the posts.

In testimony whereof I hereunto set my hand in the presence of two subscribing witnesses.

MARK JORDAN WOODHULL.

In the presence of—

FORÉE BAIN,
MARY F. ALLEN.
